UNITED STATES PATENT OFFICE.

JOHN F. OHMER AND ELMER H. BRIDENBAUGH, OF DAYTON, OHIO, ASSIGNORS TO OHMER FARE REGISTER CO., OF ROCHESTER, NEW YORK.

TICKET ISSUING AND RECORDING MACHINE.

No. 892,876.

Specification of Letters Patent.

Patented July 7, 1908.

Application filed February 12, 1906. Serial No. 300,587.

To all whom it may concern:

Be it known that we, JOHN F. OHMER and ELMER H. BRIDENBAUGH, citizens of the United States, residing at Dayton, in the county of Montgomery and State of Ohio, have invented certain new and useful Improvements in Ticket Issuing and Recording Machines, and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in ticket issuing and registering machines of the type shown and described in Letters Patent No. 779,557, issued to John F. Ohmer and 20 Elmer H. Bridenbaugh, January 10, 1905, and the application of same parties filed October 7, 1905, Serial No. 281,750, and the application of John F. Ohmer Serial No. 285,933, filed Nov. 4, 1905.

25 The present invention comprises certain improvements along the lines of the constructions shown and described in the patents and the patent applications above referred to, and said invention relates to means for insuring a positive and accurate operation of the mechanism of the machine. In a word, the means employed make it impossible to issue a ticket for a specific fare or value paid and to register that of another 30 specific fare or one of a different value.

The invention further comprises means for locking the feed roll to prevent more than one ticket at a time being fed with each operation of said feed roll.

40 The invention further provides means for separating the pressure roller from the feed roll for the purpose of applying the tickets for operation. For each separate counter there is provided an indicator designating 45 the fare or the value it represents, and each indicator has its corresponding reference on the index which is visually exposed. A pointer moving along the visually-exposed index will indicate the desired fare or value 50 to be punched and registered. The pointer is connected to the ticket or fare punch and to the detail counters so that when said pointer indicates a specific fare or value on the index, the punch will punch the same 55 or corresponding fare or value on the ticket, and it will be registered on the specific coun-

ter corresponding therewith. The tickets are previously printed and may be consecutively numbered when placed in the machine. These tickets may of course be 60 printed to subserve any purpose where units figure as a basis of value, or they may be printed to indicate other data, such as tickets, transfers, pass, or otherwise. The data on the tickets pertaining to the fare or 65 value must correspond to the index of the machine.

The object of the invention is—first, to provide means whereby, upon the initial movement of the machine, a continuous and 70 complete operation must be made, and at the same time by the initial movement the detail specific counters and the detail specific indicators and also the dial indicator are all positively locked against operation 75 until a ticket has been issued and registered.

Another object of the invention is—to prevent movement of the operating mechanism while the detail counters are being moved or set to operative positions, or the 80 detail counters in combination with the detail indicators, the punch and the exposed indicator are being moved.

The present invention in one respect differentiates from the pending application, 85 Serial No. 285,933, to which reference has been made to detail counters. In said pending application said detail fare counters are mounted securely to a supporting frame and the actuator is moved concurrently with the 90 pointer to actuate a specific counter and to indicate the corresponding fare on the indicator. In the present invention, the detail fare counters are mounted upon a hub which is rotatable on a shaft so that any one of said 95 detail fare counters may be moved to its operating position. The present invention also comprises a detail counter which actuates with any one of the detail fare counters.

Preceding a detail description of our invention, reference is made to the accompanying drawings, of which—

Figure 1, is a front elevation of the machine with the inclosing case removed. Figs. 2 and 3, are elevations of opposite sides 105 with the inclosing case in section. Fig. 4, is a sectional view on the line $y-y$ of Fig. 1. Fig. 5, is a sectional view on the line $x-x$ of Fig. 1. Fig. 6, is a top plan view, the casing appearing in section. Fig. 7, is a sectional 110 view on the line $V-V$ of Fig. 1, Fig. 8, is a detached side elevation of the assembled de-

tail fare counters. Fig. 9, is a detail elevation of the mechanism for locking the detail counters in their set positions. Fig. 10, is an illustration of a ticket issued from the machine and adapted for home or domestic purposes. Fig. 11, is a ticket adapted to foreign use, for example, in England. Fig. 12, is a view of a rear portion of the casing showing the sight opening through which the 10 fare counters are readable.

In a detail description of the invention, similar reference characters indicate corresponding parts.

The frame-work consisting of the various 15 parts A, is inclosed within a suitable casing B which is preferably opened from the rear, and in the lower portion of which the ticket roll C is located. The tickets upon this roll may be printed in either of the forms shown 20 in Figs. 10 and 11, or in any other form meeting the requirements of the road or transportation line for which they are designed, and they may or may not be consecutively numbered. The ticket strip passes 25 upwardly in the rear of the machine between an inner wall D and an outer perforated wall E and thence forwardly at the top of the machine through guide walls D' and E', emerging at the front of the machine as shown in 30 Fig. 5. The tickets are advanced or fed out of the machine, one ticket length at a time, by means of a feed roll F which has a suitable number of peripheral teeth F' to insure a proper engagement with the ticket strip. 35 The ticket-feeding roll is mounted upon a shaft G having suitable bearings in the frame and upon one end of which a pinion G' is located which is engaged by a large driving gear H rigidly mounted upon shaft H'. Upon the 40 shaft H' there is rigidly mounted a ratchet wheel H'' which is engaged by a pawl I carried upon the operating lever J, upon each upward movement of said operating lever. The operating lever is returned to its upper 45 position as shown in Fig. 5, by a spring J' which is coiled about the shaft H' and has one end connected in an adjacent part of the frame-work, and the other end projected under the pawl I.

50 Leaving the operating mechanism for a moment, we will refer to the pressure roller F'' (Fig. 6) which cooperates with the feed roll F in feeding the ticket strip. This pressure roller lies immediately above the feed 55 roll and is journaled in a frame F' pivoted to the adjacent sides of the main supporting frame. The frame F' is moved against the down pressure of a spring F'' upon its pivotal support by means of an arm F' that extends 60 from said frame and is engaged by an angular lever F' in the outward movement of the upwardly-extended end of said lever as shown in Fig. 2. In the position of the supporting frame F' as shown in Figs. 1 and 2, 65 the pressure roller is in operative relation

with the feed roll F. In elevating said pressure roller for the initial insertion of the ticket strip, the lever F' is moved outwardly at the upper end to cause the lower end of said lever to engage and lift the arm F'.

In order to prevent the withdrawal of the ticket strip from the machine other than in the normal operations of the machine in issuing tickets, we provide mechanism illustrated in Fig. 2, and consisting of a ratchet wheel K fastened to the outer face of the main spur wheel H, an angular lever K' pivoted at K'' and normally held in a position to be engaged by a lug K' which projects from the main operating lever J. The lever K' has a tooth K' which drops onto the periphery of the ratchet wheel K when said lever is free from contact with the lug K' on the operating lever J. The forward end of said lever K' is shaped to be guided by a stud K' which projects from the frame. A spring K' on the lower end of the lever K' holds said lever normally in a position for its forward end to be engaged by the lug K' when the lever J moves up. When the operating lever J is moved down preparatory to the upward or ticket-feeding movement thereof, the tooth K' engages the ratchet wheel K, and if the operating lever J is stopped at any point of its ticket-feeding stroke, less than a complete movement thereof, and an effort is made to withdraw the ticket strip by the fingers of one disposed to tamper with the machine, the feed roll so actuated by the withdrawal of the strip, will cause the main gear wheel H to be rotated by 100 the pinion G' on the shaft of the feed roll, and likewise the ratchet wheel K will be rotated with said gear wheel H until a tooth in said ratchet wheel arrives in a position to receive the tooth K' on the locking lever K'. At this time the feed roll is arrested in such movement and the ticket strip cannot be further withdrawn by the fingers. In completing the upward movement of the operating lever J, the lug K' engages the projecting end of the locking lever K' and elevates said lever from engagement with the ratchet wheel K. It will be understood that this locking lever K' is only effective when an attempt is made to withdraw the ticket strip 110 without operating the lever J.

a designates a vertical series of punches designed to punch selected portions of the tickets upon the downward movement of the operating lever J, and a' and a'' designate 120 two upper or horizontal punches, the former of which operates in connection with the detail fare counters hereinafter described, and the latter punch, to-wit—a'' operates in connection with the names of the stations or 125 other selected matter appearing on the tickets. The vertical series of punches are operated to punch the tickets by means of a series of actuators b. These actuators b are connected by a link b'—Fig. 7, more clearly 130

shown in our former application Serial No. 285,933 hereinbefore referred to. The upper actuators *b* are also connected in a manner similar to the illustrations and descriptions of said former applications, and said actuators are operated from a common pitman *c* which is operated by a shoulder on the inner end of the operating lever in a manner similar to that shown and described in said former applications. The punches *a* and *a'* are set by hand to the desired points, but the punch *a'* is set in accordance with the positions of the fare pointer *d* which points to the fare indications on the indicator *d'*, arranged on the top of the machine as shown in Fig. 6. The numbers on the indicator *d'* designate the detail fare counters *e* which will be presently described in detail. The punch *a'* is automatically shifted through a bar *f'* to one end of which the fare pointer *d* is attached—see Figs. 5 and 6. The detail counters just referred to are designated 5—10—15—20—25 and T which stand for fares of corresponding values and as per the tickets issued. These are the indications on the indicator *d'* and when the pointer *d* is moved to positions to indicate said characters on said indicator *d'*, the punch *a'* is correspondingly moved to a position to punch the fare upon a ticket thus indicated.

Referring to Fig. 6, of the drawings, and the ticket shown in Fig. 10, the punch would punch the 15¢ fare shown on said indicator and appearing on said ticket. Each fare is recorded on its own individual fare counter *e*. These counters are grouped around a common center consisting of a shaft *g* upon which they are mounted through an intervening hub *h* to which the counters are uniformly attached. Inclosing the counters so mounted, is a housing *h'* which extends over the spaces intervening between said counters—see Figs. 7 and 8. The fare denomination of each counter is also inscribed on a portion *h''* of said housing adjacent to the respective counters. These indicators *h''* adjacent to the counters may be termed "counter indicators" as they serve to identify each counter with its respective fare value. The said indicators are movable with the counters upon the shaft *g* as the counters are rotated in a body in the operation of setting a selected counter to its operative position. The visual or stationary indicator *d'* also corresponds with these counter indicators as will be readily understood. The arbor of each counter is provided with a spider or star wheel *e'* which lies on the exterior of the counter casing and in a position to be engaged by a pin *e''* projecting from an arm *e³* fixed to one side of a pinion *e⁴*. The star wheel *e'* of any of the fare counters is uniformly tripped by the pin *e''* when a respective counter is moved to a position for its respective star

wheel *e'* to be engaged by the pin *e''* when the pinion *e⁴* is actuated as presently described. The pinion *e⁴* is in mesh with a large spur wheel *m* fast on the shaft *H'* which as before stated, also supports the main driving gear *H*, said gear *m* being on the inner end of the shaft and receiving its operative movement upon the upward or feeding movement of the main operating lever *J*. It will therefore, be understood that the detail fare counters are operated simultaneously with the issuance of the tickets.

n designates a total counter which registers all the fares irrespective of their values, and as registered on all of the detail fare counters; this totalizing counter *n* is also operated from the spur gear *m* through a pinion *n'* on the arbor of the totalizing counter. The pinion *n'* is of a diameter corresponding to the diameter of the pinion *e⁴* through which the detail counters are operated as before stated; the ratio of movement between the spur wheel *m* and the pinions *e⁴* and *n'* is approximately 5 to 1. The hub *h* upon which the detail counters are mounted, is itself rigidly connected to a spur wheel *L* which is engaged by a pinion *L'* from which it receives movement to set a selected detail fare counter in operative relation with the pinion *e⁴*. The pinion *L'* is on a shaft *L''* which extends on one side of the frame and casing and has upon its projected end a finger piece *L³* by which the pinion is turned to the desired extent to set the selected fare counter. Upon the shaft *g* of said fare counters there is also mounted a notched disk *m'* which serves to arrest the setting movements of the fare counters and to hold them in their set positions. Co-operating with this notched disk is a pawl *m''* pivoted to the frame at a point above the disk and normally pulled in contact with the disk by a spring *m³*. When the disk *m'* and the assembled fare counters are rotated through the finger-piece *L³*, the pawl *m''* rides out of and into the notches in said disk and thus the setting movements of the fare counters are arrested at the proper time and said counters are held in position until the next succeeding setting operation.

It will be understood that these setting operations are arrested when the selected fare counter has been moved to the proper position to bring the star wheel thereof in position to be engaged by the pin *e''* projected from the pinion *e⁴* as hereinbefore described and as shown in Fig. 8.

It will be understood that the necessary movements of the detail counters are first determined by the position of the pointer relative to the fare indicator located on the top of the machine casing as shown in Fig. 6. The movement of the pointer and the concurrent movement of the punch *a'* herein-

before referred to, are simultaneous with the movement of the detail fare counters, and such movement takes place through mechanism now to be described. On the shaft g upon which said detail fare counters are mounted, there is an internal cam M which actuates a vertically-movable plate or bar M' through means of a pin M'' on the lower end of the said plate or bar; this pin M'' projects into the slot in the cam, such slot being of a proper curvature to elevate and lower said plate or bar M' the proper extent during the setting operations of the counters, to give an upright lever N the necessary movement for the purposes presently described. The lever N is fulcrumed at N' on a bracket N'' projected from the frame, and said lever has its short end N^* projected through a slot M^* in the plate or bar M' . It will be seen that when the bar or plate M' is elevated or lowered as the case may be, the lever N will be oscillated to an extent corresponding to the movement of said plate or bar, for example, an elevation of the plate or bar M' will cause said lever to be moved inward while the lowering of the said plate or bar will impart an outward movement of the lever. The upper end of the lever N has a suitable connection with the lower portion of the indicator or pointer d through which the fares are indicated concurrently with the setting of the detail fare counters as before stated—see Figs. 1 and 6. It will be borne in mind that in rotating the fare counters through the finger-piece L^* to bring a selected counter in operative position with the pinion e^* , the lever N is actuated to an extent corresponding to the movement imparted to the counters, and that such movement of the lever is imparted to the indicator d and the punch a' .

Means are provided for preventing an actuation of the ticket-feeding and ticket-punching mechanism when the counters and fare indicating devices and the punch a' are being moved to their operative positions, or until such positions have been reached through the movement of the finger-piece L^* . These means consist of double locking devices which serve as positive means for preventing a movement of the operating lever J until the setting operations have been completed. Initially such means consists in extending the pawl m'' as at m^* in the path of a ratchet wheel m^* which is on the adjacent end of the main shaft H' ; this extension m^* engages a tooth on the ratchet wheel m^* when the pawl m'' rides on the highest periphery of the disk m' ; at such times the main shaft H' is locked against movement. In addition to this mechanism, there is further means provided for preventing the fare counters from being operated as the main operating lever J is being lowered, and also for preventing the main operating lever from being lowered

until each complete setting operation of the fare counters has taken place. This mechanism is more clearly illustrated in Fig. 1, of the drawings, and consists of an angular lever having two arms O and O' extending at right angles; the upright portion O extends in proximity to the operating lever J and has a cam or tapered portion O'' which is engaged by said lever when the latter is depressed, and when said lever O and O' is free to be moved by said lever J . The arm O' of said lever projects above an arm O^* extending from the pawl m'' —see Fig. 9. When the pawl m'' is riding upon the highest point or points of the notched disk m' , in the setting movements of the fare counters, the end O^* of said pawl is in contact with the over-projecting end of the arm O' , and the lever O and O' is thus held with the upright portion O thereof immediately in line with the operating lever J . In this position, it is clear that the operating lever cannot be depressed, not only because the extension m^* of the pawl m'' is in engagement with the ratchet wheel m^* , but because the upright portion O of the angular lever is in the path of the movement of the said operating lever J .

When the setting movements of the fare counters are completed, the arm O^* of the pawl m'' moves down away from the arm O' of said lever and thus permits the main operating lever J to move the upright portion O out of its path which it does by engaging the cam surface O^2 . When the lever O and O' is thus shifted out of the path of said lever J , the arm O' descends in contact with the extension or arm O^3 of the pawl m'' and thus locks the fare counters against any movement until the operation of the main lever J is completed. The ratchet wheel m^* also trips in each operation, a lever P pivoted adjacent thereto and carrying a bell hammer P' which strikes a bell P'' . The pawl I which cooperates with the main operating lever J and the ratchet wheel H'' in the feeding operations of the feed roll F , is prevented from reengaging the tooth of the ratchet wheel from which it was disengaged in the initial downward movement of the main operating lever J by a detent I' . This detent normally rests upon the end of the pawl I when the operating lever is in its normal or upper position, as in Fig. 5; as the said lever is given its initial downward movement, the detent I' drops on the tooth of the ratchet wheel H'' which has thus been vacated by the pawl I , and the said detent prevents said pawl from reengaging said ratchet tooth in the event of an attempt to return the main operating lever to its upper position without completing the down stroke of said lever. The said operating lever J must be moved to its lower limit in order that the pawl I may engage the next lower tooth on the ratchet wheel. This is a safe-guard

against an improper operation of the ticket punches in the machine; the said punches are actuated to punch the tickets in the initial downward movement of the main operating lever, it will therefore be seen that if said lever is permitted to return to its upper position, before a completion of its down stroke, the punch must be caused to needlessly punch the ticket. With the preventative means just described, the possibility of improper operations of the punches is prevented.

The index pointer *p* is movable by the fingers to positions to indicate the points or stations to which the tickets are issued, said indicator being on the top of the machine and connected with the upper punch *a'* by means of bar *f*; this feature is similar to mechanism shown in the former application hereinbefore referred to.

Having described the invention in all its essential particulars and having referred to certain features which are similar to features embodied in prior applications hereinbefore referred to, we will now briefly describe an operation of the machine.

The machine being supplied with the necessary roll of tickets *C* with the leading end passed out through the ticket-opening in the upper front of the machine as shown in Fig. 5, the selected fare indication, the selected fare counter, and the punch *a'* are moved to the proper positions by turning the finger-piece *L*; the operating lever *J* is then depressed during which movement the punches punch the ticket at the various selected points. The destination and the fare value being punched by the two upper punches, and the lower series of punches punch the directions, the dates, and the months, etc. The upper or return movement of the operating lever *J* feeds forward the ticket thus punched and simultaneously with such feeding movement, the detail fare counter of that particular value of fare is actuated through the pinion *e'*, and the total counter is operated through its respective pinion *n'*. The counter indicators *h'* which are movable as before stated with the counters, are necessary in enabling one counter to be distinguished from the other, or to determine the fare value of each counter. The readings may be taken from these counters through a sight opening in the rear of the casing through which the counters are visible as shown in Fig. 12.

We claim:

1. In a ticket-issuing machine, a series of banks of counting wheels revoluble upon a common axis and upon their individual axes, a single actuating device on the shaft of each bank of counting wheels, a common actuating device for all the banks of counting wheels, said common actuating device imparting movement to the single actuating

device of any of the banks of counting wheels, means for moving the banks of counting wheels to bring the single-actuating device of any selected bank into operative relation with the common actuating device, and means for operating said common actuating device.

2. In a ticket-issuing machine, a series of banks of counting wheels revoluble upon a common axis and upon their individual axes, a single-actuating device upon the shaft of each bank of counting wheels, a common actuating device for all the banks of counting wheels, said common actuating device imparting movement to the single-actuating device of any of the banks of counting wheels, a main operating member in permanent engagement with said common actuating device, means for moving the banks of counting wheels to bring the single-actuating device of any selected bank into operative relation with the common actuating device, devices for issuing tickets, and means actuated during the issuance of a ticket to impart movement to said common actuating device.

3. In a ticket-issuing machine, a series of banks of counting wheels revoluble upon a common axis and upon their individual axes, a single-actuating device upon the shaft of each bank of counting wheels, a common actuating device for all the banks of counting wheels, said common actuating device imparting movement to the single actuating device of any bank of counters, a main operating member in permanent engagement with said common actuating device, means for moving any of the banks of counting wheels to bring the single-actuating device thereof into operative relation with the common-actuating device, and an indicator actuated through the setting movement of said bank of counting wheels to indicate the fare to be registered on said counting wheels.

4. In a ticket-issuing machine, a series of banks of counting wheels revoluble upon a common axis and upon their individual axes, a single-actuating device upon the shaft of each bank of counting wheels, a common actuating device for all the banks of counting wheels, said common actuating device imparting movement to the single actuating device of any of the banks of counting wheels, a main operating member in permanent engagement with said common actuating device, means for moving a selected counter to a position to be actuated by the common actuating device through the single actuating device of said counter, means for indicating the fare to be registered upon said counter simultaneously with the movement of the counter to its operative position, and means for actuating the common actuating device.

5. In a ticket-issuing and registering machine, a group of counters, an indicator mov-

- able simultaneously with the setting movements of said group of counters to indicate the fare to be registered on a selected counter, a punch movable simultaneously with said fare indicator to a position to punch in a ticket the fare indicated and registered, and means for simultaneously setting a selected counter, indicating the fare of said selected counter, and placing the punch in operative position with such ticket.
6. In a ticket-issuing and registering machine, a series of banks of counting wheels rotatable upon a common axis and upon their individual axes, a single actuating device upon the shaft of each bank of counting wheels, a common actuating device for all of the banks of counting wheels, said common actuating device imparting movement to the single actuating device of any of the banks of counting wheels, a main operating member in permanent engagement with said common actuating device, means for moving any of the banks of counting wheels into a position for the single-actuating device thereof to be 25 acted upon by said common actuating device, an indicator movable simultaneously with the movement of said counter to indicate the fare to be registered upon said counter and ticket-feeding mechanism actuated by the main operating member to feed a ticket, the value of which is indicated upon said indicator, and which ticket is registered upon said counter.
7. In a ticket-issuing machine, a series of 35 banks of counting wheels revolute upon a common axis and upon their individual axes, a single-actuating device upon the shaft of each bank of counting wheels, a common actuating device for all the banks of counting wheels, said common actuating device imparting movement to the single-actuating device of any of the banks of counting wheels, a main operating member in permanent engagement with said common actuating device, 40 means for moving a selected counter to a position to be operated by the common actuating device through the single-actuating device of said counter, a totalizing counter to register the fares in total, and means for simultaneously operating the selected counter through the common actuating device, and the total counter.
8. In a ticket-issuing and registering machine, a group of counters rotatable upon a common axis, indicators to indicate the fares registered on said counters, means for simultaneously setting a selected counter in an operative position and indicating the fare of such counter, ticket-punching mechanism, 55 ticket-feeding devices, and means for preventing an actuation of the ticket-feeding and ticket-punching mechanisms when the counters and ticket-punching mechanism are being moved to their operative positions.
- 60 9. In a ticket-issuing and registering machine, fare counters, a fare indicator operatively connected with said counters, a punch operatively connected with said indicator, and means for simultaneously setting said punch, said indicator and a selected fare 70 counter.
10. In a ticket-issuing and registering machine, fare counters, means for setting a selected fare counter to an operative position, ticket-issuing devices, and means for preventing an operation of said ticket-issuing devices during the setting movement of a selected fare counter, said means comprising a double-acting pawl and ratchet wheels interposed between the common shaft of the 75 counters and the shaft of the counter actuating and ticket-issuing devices.
11. In a ticket-issuing and registering machine, a plurality of specific fare counters, an actuating device common to all of said counters, means for setting a selected counter in operative relation with said actuating device, a ticket-feeding lever, and means thrown in the path of said lever during the setting movement of the fare counters to prevent a ticket from being fed when a counter 80 is not in an operative position.
12. In a ticket-issuing and registering machine, a plurality of specific fare counters, means for placing a selected one of said counters in a position to be actuated to register a fare, an indicator to indicate such fare, a punch to punch such fare in a ticket, a lever connected with said punch and said indicator, a cam rotatable with the fare counters, and means interposed between said cam and said lever for imparting setting movements to the indicator and the punch concurrently with the setting movements of a selected fare counter.
13. In a ticket-issuing and registering machine, a plurality of specific fare counters rotatable upon a common axis, means for actuating said counters in a body to bring a selected counter to an operative position, a 100 main operating lever, means actuated thereby to impart movement to a selected one of said fare counters, and means for arresting said counters in their set position during the setting movements thereof, said arresting means also preventing the movement of the operating lever while the counters are being set to their operative positions.
14. In a ticket-issuing and registering machine, a feed roll, an operating lever therefor, 105 and means engaging said operating lever for preventing a rotation of said feed roll independent of that imparted by the operating lever.
15. In a ticket-issuing and registering machine, a feed roll, an operating lever, means interposed between said lever and said feed roll for actuating the latter, and means engaging said operating lever and operated through any independent movement of said 110

feed roll for preventing a withdrawal of the ticket strip independently of the operations of said feed roll through the operating lever.

16. In a ticket-issuing and registering machine, a feed roll, an operating lever for actuating the same, mechanism for preventing movements of the feed roll independent of the operating lever, said mechanism being under the control of the operating lever during the ticket-feeding movement of said lever and said feed roll.

17. In a ticket-issuing and registering machine, a fare indicator and a fare punch movable in unison, a plurality of fare counters movable in unison with said punch and indicator in setting a selected counter in operative position, a feed roll, actuating means for said feed roll operative in one direction to punch a selected ticket as per the indicator, and operative in another direction to issue said ticket and record it on the selected counter.

18. In a ticket-issuing and registering machine, a fare indicator and a punch movable in unison, a plurality of fare counters to register the specific fares indicated, said fare counters being movable in unison with the punch and indicator to set a selected counter, a feed roll, and means for actuating said punch to punch the fare in a selected ticket, and means for simultaneously actuating the feed roll to feed said ticket after such punching, and to actuate the selected counter to register the fare so punched.

19. In a ticket-issuing and registering machine, detail fare counters, a punch to punch the fares from tickets registered on said counters, an indicator to indicate the fare punched and registered, means for placing a selected counter in operative position, means for moving the punch and the fare indicator to operative positions in the setting of the selected counter, and means for simultaneously feeding a punched ticket and actuating a selected counter.

20. In a ticket-issuing and registering machine, a plurality of detail fare counters, means for setting a selected counter in operative position, a feed roll, operating devices for concurrently actuating a selected fare counter and said feed roll, and means for preventing a setting operation of the fare counters during the operation of feeding a ticket from said roll, and registering the fare thereof on a selected counter.

21. In a ticket-issuing and registering machine, a plurality of detail fare counters, means for setting a selected counter in operative position, a feed roll, operating devices for concurrently actuating a selected fare counter and said feed roll, a fare indicator to indicate the fare registered upon said selected fare counter, and means for preventing a setting operation of the fare counters and said

fare indicator during the operation of feeding a ticket and registering the same.

22. In a ticket-issuing and registering machine, a ticket punch, a fare indicator, a plurality of detail fare counters, means for simultaneously setting a selected fare counter and said ticket punch and said fare indicator to positions to punch and indicate the fare to be registered on the selected fare counter, a feed roll, and common operative means for actuating said punch and for simultaneously feeding a punched ticket and actuating the selected fare counter to register the fare punched from said ticket.

23. In a ticket-issuing and registering machine, a plurality of detail fare counters, means for setting a selected fare counter in operative position, a punch to punch the fare of such selected counter from a ticket, a feed roll for feeding said punched ticket, an operating lever for actuating said punch in one of its movements, means interposed between said punch and said lever for transmitting movement from the lever to the punch, means for actuating the feed roll interposed between said lever and said feed roll and operative in the return movement of said lever, further means interposed between said lever and the selected fare counter for concurrently actuating the feed roll and the counter, and means actuated by said lever to lock the counters in their set position during the operation of issuing and registering a ticket.

24. In a ticket-issuing and registering machine, a plurality of detail fare counters, means for setting a selected counter in operative position, a totalizing counter to register the specific fares, a feed roll, means for simultaneously actuating said feed roll to feed a ticket and said selected fare counter to register the fare of such ticket, and means engaging the common shaft of the counters for preventing a setting operation of the detail fare counters during the operation of issuing a ticket and registering the fare thereof.

25. In a ticket-issuing and registering machine, a plurality of detail fare counters rotatable upon a common axis, means for setting a selected counter in an operative position, a punch and indicator to punch and indicate the specific fare as registered on a selected counter, an oscillating arm to impart uniform movement to said punch and said indicator, a cam rotatable upon the axis of the specific fare counters, and a connection between said cam and said arm for transmitting an oscillating movement to the arm from the rotary movement due to the setting operation of the detail fare counters.

26. In a ticket-issuing and registering machine, a feed roll, a pressure roller cooperating with said feed roll, a pivotal support for said pressure roller, means for maintaining said pressure roller in operative relation with

- the feed roll, an arm extending from said pivotal support, and an angular lever engaging said arm, said lever having its rearward end extended parallel with the back of the casing 5 of the machine.
27. In a ticket-issuing and registering machine, a main operating lever, means operated thereby for feeding previously-printed tickets from a continuous strip, a separate 10 counter for registering fares of different denominations during the feeding of the tickets, means operated by said main operating lever and actuating the counter of any class of fares, means for punching the fare value from 15 each ticket before its issuance, means actuated by said main operating lever to operate said punching means, and means for indicating the value of each ticket before the same is punched.
28. In a ticket-issuing and registering machine, means for feeding tickets having a plurality of different fare values printed thereon, means for punching the fare value of each ticket, means for indicating the fare value 25 of such ticket before punching, a selected counter for registering each denomination of fare as indicated, and as punched from the ticket, and means for simultaneously setting the punch, the indicator and the selected 30 counter.
29. In a machine of the class specified, means for feeding tickets having a plurality of different fare values printed thereon, means for punching each ticket to indicate 35 the fare value thereof, means for indicating the fare value of such ticket before punching, a selected counter for registering each denomination of fare as indicated and as punched from the ticket, means for simultaneously setting the punch, the indicator and the selected 40 counter, a totalizing counter, and means for actuating the selected counter simultaneously with the totalizing counter.
30. In a machine of the class specified, the 45 combination of a plurality of specific counters, a punch, a setting shaft for moving the counters and punch to actuating positions, and means to actuate the counter and punch when moved to such positions.
31. In a machine of the class specified, the 50 combination of a plurality of counters, a punch, an indicator, a setting shaft for moving the counters, the punch and indicator to actuating positions, and means to actuate the counter and punch after being moved to such positions.
32. In a machine of the class specified, the 55 combination of a plurality of counters, a punch, a shaft upon which the counters are mounted, a setting shaft geared to said first named shaft for moving the counters and punch to actuating positions, and means to actuate a specific counter and the punch after being moved by said setting shaft.
33. In a machine of the class specified, the 60 combination of a plurality of counters, a punch, an indicator, a shaft upon which the counters are mounted, a setting shaft geared to said first named shaft for moving the counters and punch to actuating positions 75 and to simultaneously set the indicator, and means for actuating a specific counter after its movement by the setting shaft.
34. In a machine of the class specified, the 70 combination of a plurality of counters and a plurality of counter indicators mounted circumferentially around a shaft, a setting shaft geared to the shaft upon which the counters and indicators are mounted for imparting movement to said counters and indicators to 80 operative positions, and common means for actuating each counter when set to an operative position.
35. In a machine of the class specified, the 85 combination of a plurality of counters each bank of said counters having an actuating wheel, and a plurality of counter indicators mounted upon a shaft and moved axially with said shaft, stationary fare indicators, an indicator pointer therefor, means for simultaneously moving the counters and counter indicators and said fare indicator pointer, and means common to all of said counters for actuating any counter brought in operative relation therewith, and said means 90 comprising a pinion with an eccentric pin.
36. In a machine of the class specified, the 95 combination of a plurality of counters and their indicators mounted upon a shaft and movable axially with said shaft, each bank of 100 said counters having a single actuating wheel, stationary indicators indicating the data on the counter indicators, a pointer for said stationary indicators, and means for simultaneously moving the counters and their indicators, and the fare indicator pointer to operative positions, and common means for actuating each counter after so moved, said means consisting of a pinion having an eccentric pin adapted to engage the 105 single-actuating wheel of any counter.
37. In a machine of the class specified, the 110 combination of a plurality of counters, a plurality of indicators, one for each counter, a punch, stationary indicators corresponding 115 to the counter indicators, a pointer therefor, and means for simultaneously moving the counters and their indicators, the punch and the indicator pointer to operative positions.
38. In a machine of the class specified, the 120 combination with a plurality of specific counters and a totalizing counter, a punch, a setting shaft for moving the specific counters, and the punch to actuating positions, and means to simultaneously actuate the punch 125 and a specific counter and the total counter.
39. In a machine of the class specified, in combination with a plurality of specific

892,876

counters, a total counter, a punch, an indicator, a setting shaft for moving the specific counters, the punch and indicator to actuating positions, and means to actuate the punch, a specific counter and the total counter, after a specific counter is moved to an actuating position.

40. In a machine of the class specified, the combination with a plurality of specific 10 counters and a total counter, of a punch, a shaft upon which the specific counters are mounted, a setting shaft geared to said first named shaft for moving the specific counters and the punch to actuating positions and 15 means to simultaneously actuate the total counter, the punch and a specific counter.

41. In a machine of the class specified, the combination with a plurality of specific 20 counters, and a total counter, a punch, an indicator, a shaft upon which the specific counters are mounted, a setting shaft geared to said first named shaft for moving the specific counters and the punch to actuating positions, and to simultaneously set the 25 indicator, and means for simultaneously actuating a specific counter, the total counter and the punch, after said specific counter, punch and indicator have been moved by the setting shaft.

42. In a machine of the type specified, a plurality of banks of counters, each bank having a single actuating device on the shaft thereof, a common actuating device comprising a pinion with a pin thereon for 35 all of the banks of counters and adapted to actuate the single actuating device of any bank of counters brought in operative relation therewith, and each of said banks of counters having its own indicator designating the class of fares for which each bank of 40 counters is utilized, said indicators being movable with the banks of counters to operative positions.

43. In a machine of the class specified, the combination with a plurality of specific 45 counters and a plurality of specific indicators, one for each counter, a total counter, a punch, stationary indicators, an indicator pointer therefor, and means for simultaneously moving the counters and their indicators, the punch and said indicator pointer.

44. In a machine of the class specified, the combination with a plurality of specific 50 counters and a plurality of specific indicators, one for each counter, a stationary indicator corresponding to the counter indicators, an indicator pointer for said stationary indicator, a total counter, means for simultaneously moving the specific counters and their 55 indicators, the indicator pointer and the punch to operative positions, and means for simultaneously actuating a specific counter, the total counter and the punch.

45. In a machine of the class specified,

the combination with a plurality of specific 65 counters, a punch, a setting shaft, and coöperating means for moving the counters and punch to actuating positions, and a lever with coöperating means to actuate a counter and said punch. 70

46. In a machine of the class specified, the combination of a plurality of counters, a punch, an indicator, a setting shaft and means actuated thereby for moving the counters, the punch and indicator to actuating 75 positions, and a lever for actuating the counter and punch.

47. In a machine of the class specified, a group of counters movable about a common axis of rotation and movable upon 80 individual axes, a series of indicators to identify said counters, said indicators being movable about said common axis, a stationary indicator to indicate a selected counter, a punch to punch the fare of the 85 selected counter, and means for simultaneously moving a selected fare counter, the stationary indicator, and the punch to operative positions.

48. In a machine of the class specified, a 90 series of groups of counters, an actuating device common to all of said counters and adapted to actuate any counter moved into operative relation therewith, an indicator to indicate the fares registered on said counters, 95 means for simultaneously moving a selected counter to an operative position and for indicating the fare of such counter, and a station indicator and a punch simultaneously movable to indicate the station to which a 100 ticket is issued and to shift the punch to a position to punch the ticket.

49. In a machine of the class specified, the combination of a plurality of counters, a shaft upon which said counters are mounted, 105 a setting shaft geared to said first named shaft for moving the counters and punch to actuating positions, and a lever with coöperating means for actuating the counters and punch. 110

50. In a machine of class specified, the combination of a plurality of counters, a punch, an indicator, a shaft upon which said counters are mounted, a setting shaft geared to said first named shaft for moving the counters and punch to actuating positions, and to simultaneously set the indicator, and an operating lever with coöperating means for actuating said punch and said counters. 115

51. In a machine of the class specified, an 120 indicator and a punch, means for moving them simultaneously, the indicator to a position to show the destination for which each ticket is issued, and the punch to a position to punch each ticket to indicate thereon 125 the destination, a series of banks of counters to register each class of tickets so indicated and punched, a common actuating device

to actuate any bank of counters moved into operative relation therewith, means for moving a selected bank of counters into operative relation with said actuating device, and means for issuing a ticket and actuating said punch.

52. In a machine of the class specified, the combination of a plurality of counters, a plurality of indicators, one for each counter, 10 a punch, a stationary indicator with indications corresponding to the counter indicators, a pointer for said stationary indicator, and means for simultaneously moving the counters and counter indicators, the punch and the indicator pointer, and a lever 15 to simultaneously actuate a specific counter and the total counter.

53. In a machine of the class specified, the combination with a plurality of specific 20 counters and a total counter, a punch, an indicator, a setting shaft and means actuated thereby for moving the counters, the punch and the indicator to actuating positions, and a lever for actuating the specific counters 25 and punch after being moved to their actuating positions.

54. In a machine of the class specified, the combination with a plurality of specific 30 counters and a total counter, a punch, an indicator, a shaft upon which the counters are mounted, a setting shaft geared to said first named shaft for moving the counters and punch to actuating positions, and to simultaneously set the indicator, and a lever 35 with coöperating means to simultaneously operate the specific and the total counters.

55. In a machine of the class specified, the combination with a plurality of specific 40 counters and a total counter, of a plurality of indicators, one for each of the specific counters, a punch, stationary indicators corresponding to the counter indicators, an indicator pointer, and means for simultaneously moving the specific counters and 45 indicators, the punch, and the indicator pointer, and a lever for simultaneously actuating the punch and the counters.

56. In a machine of the class specified, the combination with a plurality of specific 50 counters, a feed roller, a punch, a setting shaft for moving the counters and punch to actuating positions, and a lever with means actuated thereby to simultaneously actuate the counters and punch.

57. In a machine of the class specified, the combination with a plurality of counters, a punch, a feed roller, an indicator, a setting shaft for moving the counters, the punch, and the indicator to actuating positions, and 60 a lever with coöperating means to simultaneously actuate the counters, the feed roller and the punch.

58. In a machine of the type specified, a plurality of banks of counters rotatable in a

body upon a common axis, each bank of 60 counters having a single actuating device upon its shaft, a common actuating device to operate any selected bank of counters through said single actuating device, said common actuating device comprising a 70 toothed member with pin thereon, a setting shaft geared to the common axis of said banks of counters and adapted to impart movement to the counters in a body to set a selected counter in operative relation with 75 the common actuating device, ticket-feeding devices, means for actuating the common actuating device of the counters, and an operating lever through which said ticket-feeding devices and said means for actuating 80 the common actuating devices are simultaneously operated.

59. In a machine of the class specified, the combination with a plurality of counters, of a punch, a feed roller, a shaft upon which 85 said counters are mounted, a setting shaft geared to said shaft for moving the counters and punch to actuating positions, and a lever with coöperating means to simultaneously actuate the counters, the punch and the 90 feed roller.

60. In a machine of the class specified, the combination with a plurality of counters, of a punch, an indicator, a feed roller, a shaft upon which the counters are mounted, a 95 setting shaft geared to said shaft for moving the counters and punch to actuating positions, means to limit the movement of the setting shaft, and a lever for simultaneously actuating the counters and punch. 100

61. In a machine of the class specified, the combination with a plurality of counters and a plurality of indicators, one for each counter, a punch, of stationary indicators, an indicator pointer therefor, means for 105 simultaneously moving the counters and their indicators, the punch and the indicator pointer, a feed roller, and an operating lever with coöperating means for simultaneously actuating the counters, the punch, and the 110 feed roller.

62. In a machine of the class specified, the combination with a plurality of specific counters, of a total counter, an operating lever, a punch, a setting shaft, and means 115 coöperating therewith for moving the specific counters and the punch to actuating positions.

63. In a machine of the class specified, the combination with a plurality of specific counters, a total counter, a punch, an operating lever and means coöperating therewith, an indicator, a setting shaft for moving the specific counters, the punch and the indicator to actuating positions. 120

64. In a ticket-issuing and registering machine, visual indicators, a pointer therefor, a shaft, and a spiral cam mounted upon said shaft for imparting movement to the pointer. 125

65. In a ticket-issuing and registering machine, a visual indicator and a pointer therefor, a punch connected to said pointer, a spiral cam for imparting the proper movement to the said pointer and punch, and means interposed between said pointer and said cam.
66. In a ticket-issuing and registering machine, a setting shaft, an auxiliary shaft geared to said setting shaft, an indicator, a spiral cam pinned to said auxiliary shaft, and means interposed for imparting movement from said cam to the indicator.
67. In a ticket-issuing and registering machine, a setting shaft, an auxiliary shaft geared to said setting shaft, an indicator, a punch, a spiral cam pinned to said auxiliary shaft, and interposed means for imparting the proper movement from said cam to the indicator and punch.
68. In a ticket-issuing and registering machine, a setting shaft, an auxiliary shaft, means intervening for arresting the movement of the auxiliary shaft, a spiral cam pinned to the auxiliary shaft, an indicator, and means intervening between said spiral cam and the indicator for imparting movement thereto.
69. In a ticket-issuing and registering machine, a setting shaft, an auxiliary shaft, means intervening for arresting the movement of the auxiliary shaft, a spiral cam pinned to the auxiliary shaft, an indicator and a punch, and means intervening between said spiral cam and the indicator and punch for imparting movement thereto.
70. In a ticket-issuing and registering machine, a setting shaft, an auxiliary shaft, a spiral cam on said auxiliary shaft, a punch, and means intervening between said spiral cam and punch for imparting movement thereto.
71. In a ticket-issuing and registering machine, a series of groups of counters each having a single-actuating device thereon, a setting shaft adapted to move a selected counter to a position to be operated, an actuating device common to all of said counters and adapted to operate the selected counter through engagement with the common actuating device, a ticket punch, means for setting said ticket punch in a position to be operated, ticket-feeding mechanism, means for actuating the punch, and means for actuating the counter-actuating device operated by said ticket-feeding mechanism.
72. In a ticket-issuing and registering machine, a setting shaft, a punch, means intervening between said setting shaft and the punch for moving the punch to an operative position, a punch-actuating device, and a lever with coöperating means for actuating the said punch-actuating device.
73. In a machine of the class specified, means to punch a ticket, means to indicate a ticket so punched, a counter to register each punched ticket, and means to prevent a second punching on the same ticket.
74. In a machine of the class specified, the combination with ticket-feeding mechanism and a main operating lever, of a punch to punch one of several fare denominations from printed tickets, means for indicating the fare denomination so punched, a series of counters one for each fare denomination, and means actuated by the main operating lever to compel a registration on the counter corresponding to the fare denomination indicated and punched.
75. In a machine of the class specified, the combination with ticket-feeding devices, comprising a feed roll, a main operating lever, and intervening gears, of means for punching each ticket to indicate the fare denomination thereof, a counter to register each ticket punched and issued, and means for preventing a second punching of the same ticket comprising a dog engaging the main operating lever, said means preventing a return to the normal position of the ticket-feeding devices before the issuance of the punched ticket.
76. In a machine of the class specified, ticket-feeding mechanism, a series of counters to register the tickets issued, an indicator for each of said counters, means for moving any one of said counters and its indicator to operative positions, means for operating a counter when so moved and during the issuance of a ticket, a punch and an indicator simultaneously movable to operative positions prior to the movement of a counter to its operative position, the indicator to indicate the denomination of fare to be registered on a counter, and the punch to punch from the ticket the fare denomination.
